[57] CLAIM

The ornamental design for an examination chair, as shown and described.

DESCRIPTION

FIG. 1 is a front perspective view of the examination chair shown in an upright position with portions thereof in phantom representing environmental matter which is not part of the claimed invention;

FIG. 2 is a top view thereof;

FIG. 3 is a left side view thereof with the right side being a mirror image of the left side;

FIG. 4 is a front view thereof;

FIG. 5 is a rear view thereof;

FIG. 6 is a bottom view thereof;

FIG. 7 illustrates a front perspective view of an alternative tilted position of the examination chair shown in FIG. 1 with portions thereof in phantom representing environmental matter which is not part of the claimed invention;

FIG. 8 is a top view of the examination chair as shown in FIG. 7;

FIG. 9 is a left side view of the examination chair as shown in FIG. 7 with the right side being a mirror image of the left side;

FIG. 10 is a front view of the examination chair as shown in FIG. 7;

FIG. 11 is a rear view of the examination chair as shown in FIG. 7; and,

FIG. 12 is a bottom view of the examination chair as shown in FIG. 7.
